UNITED STATES PATENT OFFICE.

CHARLES ROYLE, OF NEW YORK, N. Y.

LAMP.

SPECIFICATION forming part of Letters Patent No. 251,952, dated January 3, 1882.

Application filed October 29, 1881. (No model.)

To all whom it may concern:

Be it known that I, CHARLES ROYLE, of the city, county, and State of New York, have invented a new and useful Improvement in Lamps, of which the following is a full, clear, and exact description.

Reference is to be had to the accompanying drawing, forming a part of this specification.

The drawing is a sectional side elevation of my improvement.

This invention relates to that class of lamps in which the oil-chamber is surrounded by, supported upon, and connected with the pedestal by a body made of ornamented porcelain, and has for its object to simplify and cheapen the construction of the said ornamented body.

The invention consists of the body made of cement molded into shape and covered with a shell of ornamented sheet metal or paper, with the oil-chamber, base, and tie-rod of the lamp, as will be hereinafter fully described.

A represents the oil-chamber of a lamp, which may be made of glass or metal, and to the bottom of which is secured the upper end of a rod, B. The rod B passes down through the base C, and has a screw-thread cut upon its lower end to receive the nut D, so that the various parts of the lamp can be fastened together by screwing the nut D upon the rod B.

The bottom of the base C is recessed to receive the nut D, so that the said nut will not come in contact with the surface upon which

the said base C stands. The oil-chamber A is provided with the flange a, which rests upon the upper edge of the body E F, and by which it is supported within the said body. The inner part, E, of the body is formed of plaster-of-paris or other suitable cement, molded into cylindrical form or other desired shape, and inclosed in a shell, F, of sheet metal or paper. 35 The shell F is painted or otherwise ornamented to imitate the porcelain body which has heretofore been used in making this kind of lamps, and which is very expensive.

Having thus described my invention, I claim 45 as new and desire to secure by Letters Patent—

1. In a lamp, the body E F, the inner part, E, of which is formed of cement molded into cylindrical form and inclosed in an ornamental shell of sheet metal or paper, F, in combination with the oil-chamber A, supported within the said body by its upper flange, and secured therein by the bolt B and nut D, substantially as shown and described. 50

2. In a lamp, the combination, with the oil-chamber A, the base C, and the tie-rod B, of the body formed of a cement inner part, E, molded into shape, and a covering-shell, F, of ornamented sheet metal or paper, substantially as herein shown and described. 55

CHARLES ROYLE.
